UNITED STATES PATENT OFFICE

2,167,504

COOLING OF CYLINDRICAL BODIES

Raymond S. Gorman, Dormont, and Ralph E. Graham, Crafton, Pa., assignors to Clifford B. Ferree, Pittsburgh, Pa.

Application June 9, 1938, Serial No. 212,746

1 Claim. (Cl. 266—6)

This invention relates to the cooling of cylindrical bodies of metal, and finds practical application in the formation by cooling of a chill upon the barrel of a forged steel roll. Its general applicability to the formation of chills upon cylindrical bodies will be manifest. The objects in view are quality, depth, and uniformity of chill throughout the extent of the cylindrical body.

In Letters Patent of the United States, No. 2,044,334, granted to Clifford B. Ferree, for Method of and apparatus for cooling rolls, a spray jacket is shown and described. The spray jacket is a double-walled cylindrical shell, of length corresponding to or somewhat exceeding that of the barrel of the roll to be cooled, and of an internal diameter such as to receive the roll with small clearance. The inner wall of the jacket is perforated with a multitude of small, closely set, evenly distributed orifices; and from these orifices, when the apparatus is in service, jets of water are projected upon the surface of a hot roll that has been brought to place within the jacket, and that stands, rotating upon a turn-table. The problem to which the invention of the said Ferree patent is addressed is the problem of flowing uniformly over every unit of area of the surface of the roll barrel, at maximum rate, and at uniform temperature, the cooling stream of water.

It has been found that, in a particular installation, the chilling effect upon the rolls was not, as had been intended, uniform. Investigation revealed the fact that it was the lower portion of the roll as it stood within the cooling apparatus that was less perfectly chilled than the upper portion; and the fact was perceived that, because of the narrowness of the interval at which the jacket was spaced from the roll surface, there was a glutting of the way of escape of the heated water downward, and that, in consequence, the withdrawal of heat proceeded at more rapid rate at the upper than at the lower end of the roll body. It is to the overcoming of that difficulty, and to the realizing in fullest measure of the benefits and advantages of the method and apparatus of the Ferree patent named above that the present invention is addressed.

In the accompanying drawings Fig. I is a view, partly in side elevation, partly in vertical section of roll-cooling apparatus in which the present invention is embodied. In this figure certain parts are broken away; and a roll is shown, in cooling position within the apparatus. Fig. II is a fragmentary view of the apparatus, partly

in plan from above, and partly in horizontal section. Certain parts shown in Fig. I are not present in the showing of Fig. II. Fig. III is a fragmentary view to larger scale, illustrating in side elevation and in vertical section certain details of structure. Fig. IV is a view in section, on the plane indicated by the line IV—IV, Fig. III. Fig. V is a fragmentary view in horizontal section, illustrating the relative positions of the roll surface and the spraying apparatus.

A roll 1 stands on end on a turn-table 3. It will be understood that this roll has been brought to high temperature in a suitable furnace, and has been quickly taken from the furnace and set in centered position upon the turn-table. It is very hot, and the purpose of the apparatus is to project upon its surface uniformly everywhere a constantly renewed surge of water of uniform, and (necessarily) of relatively low, temperature.

The apparatus includes, in combination with the turn-table 3, the spraying device. This consists of a cage whose bars 4 extend vertically and stand in cylindrical assembly, surrounding the roll in place on the turn-table. The bars are hollow, for the conveyance of water; they are provided each with a line of orifices 41, opening toward the roll body; they stand spaced at a uniform interval from the roll body; and they are spaced apart, at equal intervals one from another. The hollow bars of the cage advantageously take the form of lengths of pipe of elongate, and specifically of oval cross-section (approximating sector shape), set with the major axis in radial position with respect to the axis of the roll, and with the small end inward. Thus maximum capacity is combined with maximum space interval between cage bars. Conveniently the bars 4 are built into a cage structure that includes upper and lower headers 46 of annular form, and to the two headers alike water under suitable pressure is supplied by appropriate connection, as the drawings show. The headers are so spaced and arranged that in the assembly the barrel of the roll is positioned wholly between them, so that throughout all its extent the barrel of the roll may be played upon by jets from the orifices in the bars.

Figs. III and IV serve to show details of suitable structure. The headers are box-like structures built of plates, and the pipes 5 at their ends (conveniently swaged to circular shape) are welded in openings of corresponding shape in the header walls.

Other features shown in the drawings are circumstantial, merely, and not essential to this

invention. The roll is shown to be provided with an axial bore, and a nozzle 6 is provided for projecting a stream of cooling water into the bore. A perforated plug 12 is shown set within the bore at the lower end, whose effect is to cause the water supplied to the bore to overflow and pour over the surface of the upper neck of the roll.

5 In operation multitudinous jets of water properly distributed impinge upon the roll surface and take up heat. The heated water passes freely away between the bars of the cage. There is no glutting, no arrest of the escape, no interference by accumulation of hot water with the cooling effect of the jets, either toward the lower end of the roll or elsewhere. The escaping water falls and may be gathered in a basin 30. Thence it may be carried away through a line 40; and, 10 if desired, after cooling, may be returned again 15 to (as by a pump, not shown) through the water supply connection 42.

Water ordinarily will be the cooling medium; manifestly, it suffices that it be a liquid.

We claim as our invention:

Apparatus for applying to a heated cylindrical body of metal an inundating flood of cooling liquid, such apparatus consisting of a cylindrical cage of hollow, vertically extending, spaced-apart bars provided with inwardly and radially directed orifices, together with means for maintaining the bars flushed with liquid under pressure, the cage being adapted to surround and to stand at an interval from the surface of the vertically standing cylindrical body to be cooled, the bars of the cage being of oval shape in cross-section and being assembled with the major axes 15 of the ovals extending in radial direction, the parts being so proportioned that quantities of liquid, injected through the orifices and impinging upon the surface of the cylindrical body, pass freely away between the bars, without glutting. 20
